UNITED STATES PATENT OFFICE.

EGBERT H. GOLD, OF CHICAGO, ILLINOIS.

CAR-HEATING SYSTEM.

1,162,767.

Specification of Letters Patent.

Patented Dec. 7, 1915.

Application filed February 27, 1915. Serial No. 11,086.

To all whom it may concern:

Be it known that I, EGBERT H. GOLD, a citizen of the United States, residing at Chicago, in the county of Cook and State of 5 Illinois, have invented certain new and useful Improvements in Car-Heating Systems, of which the following is a specification.

My invention relates to a heating system for railway cars and the invention has for 10 its object the provision of certain improvements in car heating systems to be herein-after described and claimed.

The invention relates more particularly to a car heating system employing as heating media both hot water and steam; the steam coils being supplied with steam, when occasion requires, to supplement the action of the hot water coils, which latter provide the sole means for heating the car under 15 ordinary conditions. In a system of this sort the water coils extend the length of the car and are arranged so that besides supplying heat to all parts of the car, they prevent the water supply pipes and fittings of the 20 car from becoming frozen up in severe weather. Because of this function of the water circulating coils, it is essential that the steam circulating coils, or at least certain of them, should be incapable of being supplied 25 with medium unless the water coils are in operation. Otherwise the attendant might, by using the steam circulating system alone, or certain parts of it, bring about a freeze-up of some of the water supply pipes or 30 other fixtures containing standing water. The supply pipe or pipes for the steam circulating coils are, therefore, arranged so 35 that they may be closed without affecting the flow of steam to the heater for the hot water system, while, on the other hand, it is not 40 possible to introduce steam into the steam circulating coils, or at least into steam coils which the attendant might use instead of 45 the water coils for heating the car as a whole, unless steam at the same time is supplied to the water heater, thereby making 50 the water circulating system active.

One of the principal objects of my invention is to provide certain constructions and 55 arrangements in a system of this sort which will simplify the apparatus, thereby reducing the cost of installation and repairs.

A further object is to provide an arrange-

ment whereby the controlling devices for the steam circulating coils are kept warm 55 enough so that they will not freeze even when this part of the system is inactive, as will ordinarily be the case most of the time.

A further object of the invention is to provide a fitting adapted to surround the 60 train pipe of the car heating system to which fitting certain of the other elements of the heating system may be attached and which provides means through which said elements are put into communication with each other. 65

The invention is illustrated, in a preferred embodiment, in the accompanying drawings showing the said improvements employed in connection with a heating system of the type above described. 70

Figure 1 is a diagrammatic view of a car heating system of this type. Fig. 2 is a side elevation of a fitting which surrounds the train pipe and to which certain elements of the heating system are attached, as will be 75 hereinafter described. Fig. 3 is a sectional plan on line 3—3 of Fig. 2. Fig. 4 is a vertical cross sectional view on line 4—4 of Fig. 2. Fig. 5 is a view, in perspective, of a group of devices for controlling the steam 80 circulating coils attached to a fitting of the kind detailed in the preceding three figures. Fig. 6 is a side view of a modified form of fitting. Fig. 7 is a plan view of the same. Fig. 8 is a sectional view taken on line 8—8 85 of Fig. 7. Fig. 9 is a diagrammatic view, similar to Fig. 1, showing a modified arrangement of the steam heating coils.

Like characters of reference designate like parts in the several figures of the drawings. 90

A brief description will be first given of the heating system shown in Fig. 1. It should be understood, however, that the improvements constituting my invention, might be employed with car heating systems different from this particular system but which are constructed and operated in accordance with the same general principles. Referring to this figure, A represents the car, B the steam train pipe, C and D water 100 circulating coils, and E the steam heater for the water circulating system, which, of course, is ordinarily inclosed in a stove (not shown in the drawings), by means of which the water may be heated by a coal fire when 105 steam is not available. The water heater E

receives steam from the train line B through a pipe F provided with a shut off valve Q. As stated, the water coils constitute the primary radiating units in the system and extend the length of the car on each side thereof and pass near all pipes, fittings and the like containing water and located so that the water therein is likely to freeze unless specially heated. When additional heat is required in the car, it is obtainable from the steam circulating coils H, I, J, K, L and M, which may be supplied with steam singly or all together, as may be desired. The supply of medium to the coils H and I is controlled by a vapor regulator N of the type shown in my Patent No. 987,567, March 21, 1911, which operates to maintain steam in the coils at a pressure approximating atmospheric pressure. These two coils are connected together and to the vapor regulator by a pair of four-way valves O, O' in an arrangement such as that shown in said Patent No. 987,567, whereby the coils may be put under steam either singly or jointly as required. The steam for coils H and I is supplied through a pipe P which is connected with the steam coils of heater E. By this arrangement it is impossible to use any of the steam coils unless the water system is in operation.

R is a fitting surrounding train pipe B, with which pipe P is connected and to which the vapor regulator N is attached and also preferably a steam trap S. R' is a similar fitting on the train pipe connected with fitting R by a pipe T and to which is attached a steam trap S' and vapor regulators N', N². The vapor regulator N' controls the supply of steam to coils L and M which are provided with a pair of four-way valves O², O³. The vapor regulator N² controls the steam supply to the circulating coils J, K, which are likewise provided with four-way valves designated O⁴, O⁵; the arrangement of the four-way valves being in each case similar to that described in connection with coils H and I.

The fittings R, R', are substantially alike so that it will suffice to describe one of them, namely, the fitting R. This device is illustrated in detail in Figs. 2 to 4 inclusive. It consists of a tubular member 10 surrounding the train pipe B and formed with lateral hollow projections 11 which are diagonally disposed with respect to the tubular member and are joined underneath one end of the tubular member by a transverse hollow member 13. The transverse member is tapped on one side for the trap S and on the other for the supply pipe P. The hollow projecting members 11 are formed with taps in their sides and ends. Into one of the side taps is threaded the connecting pipe 14 of the vapor regulator N. The opposite side tap is closed by a plug 15. The pipe T

connecting the fitting R with the fitting R' is threaded into one of the end taps, the other one being closed by a plug 15'. The connection between the vapor regulators N', N², the trap S', pipe T and the fitting R' will be understood by reference to Figs. 1 and 5.

Operation: When heat is required in the car in excess of the capacity of the primary or water circulating coils C and D, one or more of the vapor or steam circulating coils are put into operation by manipulation of the appropriate four-way valves O, O', etc. Assuming that coils H and I are thus put into operation, steam passes from the steam coils of the water heater through pipe P to the fitting R, through the duct 16 on one side of the fitting into the vapor regulator N and thence through the coils H and I (or whichever one is open, if only one is open), the medium outflowing through the vapor regulator in the manner described in my patent above referred to. When the coils H and I are cut out again, which is accomplished through the manipulation of the four-way valves O, O', the steam will continue to flow in small amounts through pipe P, duct 16 and the pipes 17 and 18 connecting the four-way valves with the vapor regulator; the amount of steam passing through this circuit being just sufficient to keep the thermostatic member of the vapor regulator expanded. The operation of the vapor regulator under these conditions is also described in my Patent No. 987,567. The heat derived from this small amount of steam, together with the heat radiated from the train pipe B in which, of course, the pressure is relatively high, is sufficient to keep the steam trap and the vapor regulator from freezing up even in very cold weather. With the steam circulatory system operative steam flows through the pipe T to the fitting R'. If none of the vapor coils associated with this fitting are active, just enough steam will pass through pipe T to keep the vapor regulators N', N² and steam trap S' from freezing. When one or more of these coils is opened up steam flows through pipe T in a volume appropriate to the amount of active radiating surface. The function of the steam traps S, S' is to purge the medium of water of condensation before it is sent through the circulating coils. If the entire steam circulatory system is cut off, by closing valve Q, the proximity of the traps S, S' and vapor regulators N, N', N² to the fittings R, R' and the train pipe B prevents these devices from being clogged with ice.

A modified form of fitting is shown in Figs. 6 to 8 inclusive. The device shown in these figures is substantially the same as that detailed in Figs. 2 to 4 inclusive, except that it is made in two parts, a lower part 19 and an upper or covered part 20, the

parts being fitted around the train pipe B and secured together by bolts 21. The lower part 19 is formed with the ducts and taps like those of the fitting previously described.

5 In addition, the lower member 19 is formed with ears 22 connected by bolts 23 to a yoke 24 hung from the under frame 25 of the car.

In Fig. 9 I have shown a heating system constructed and operated upon the same 10 general principles as the heating system shown in Fig. 1 but modified so as to be particularly suitable for a sleeping car containing state rooms, lavatories or smoking rooms which may require heat even when it is un-

15 desirable to heat, even with the water coils, the main or berth section of the car. To meet this contingency certain portions of the car, for example the state room, the ladies' lavatory and the smoking room, are provided 20 with steam coils which can be supplied with steam directly from the train pipe so that these rooms may be heated even though the water circulating system is inactive. The auxiliary steam heating coils for the

25 main or berth section of the car, as in the system previously described, may be supplied with steam only when the water system is in operation. There is no danger that the attendant will attempt to use the auxiliary steam coils for the special compartments when the whole car needs heat, in place of the water coils, and thereby cause a freeze up in the system because the steam coils in the special compartments, the state 30 rooms, lavatory and smoking room, will be so obviously ineffective for this purpose that no such mistake can be made.

The body of the car, in Fig. 9, is indicated at A', the smoking room at 32, the 40 ladies' lavatory at 33, the state room at 34, and the berth section of the car at 35. The elements of the heating system, which are the same as in the arrangement of Fig. 1, are given corresponding reference characters and will not be particularly described. The berth section 35 of the car is shown as provided with three auxiliary steam coils U, U', U² which receive steam through pipe P and fitting 26, the control of these coils being effected by vapor regulators N³, N⁴ and 45 four-way valves O⁶, O⁷, O⁸, the arrangement and operation of which is the same as the corresponding devices in the Fig. 1 system. The ladies' lavatory 33 and the state room 50 34 are provided with steam coils V, W, supplied with steam directly from the train pipe B through a circuit 36 in which is arranged a vapor regulator N⁵ and four-way valves O⁹, O¹⁰, the arrangement of the four- 55 way valves O⁹, O¹⁰ being the same as that of four-way valves O, O' shown in Fig. 1, whereby either coil may be supplied singly or both together, in which latter case the medium flows first through one and then 60 through the other. The smoking room 32

is similarly provided with a steam coil X supplied directly from the train pipe by means of a circuit 37 in which is a vapor regulator N⁶ and a four-way valve O¹¹.

I claim:

1. In a car heating system, the combination with a train pipe of radiating means, a hollow fitting surrounding the train pipe, a supply pipe leading into said fitting, a fluid conduit connecting the fitting with the radiating means, and controlling devices for said radiating means which are attached to and lie adjacent to said fitting and communicate with the interior thereof. 75

2. In a car heating system, the combination with a train pipe of radiating means, a hollow fitting surrounding the train pipe, a supply pipe leading into said fitting, a fluid conduit connecting the fitting with the radiating means, a vapor regulator for controlling the flow of steam into said radiating means which is attached to and lies adjacent to said fitting and communicates with the interior thereof. 80

3. In a car heating system, the combination with a train pipe of radiating means, a hollow fitting surrounding the train pipe, a supply pipe leading into said fitting, a fluid conduit connecting the fitting with the radiating means, a vapor regulator for controlling the supply of steam to said radiating means and a steam trap, both of which are attached to and lie adjacent to said fitting and communicate with the interior thereof. 90

4. In a car heating system, the combination with a train pipe of radiating means, a fitting comprising a tubular member which surrounds the train pipe and is formed with hollow lateral projections and a transverse hollow member connecting the same, a supply pipe leading into said fitting, a fluid conduit connecting the fitting with the radiating means, and controlling devices for said radiating means which are attached to and lie adjacent to said fitting and communicate with the interior thereof. 105

5. In a car heating system, the combination with a train pipe of radiating means, a hollow fitting comprising a tubular member surrounding the train pipe formed with hollow lateral obliquely disposed projections and a transverse hollow member connecting the same to a vapor regulator attached to said fitting at the upper end of said hollow projection, a steam trap secured to the fitting at the lower end of said projection, and a fluid conduit connecting the train pipe with the radiating means and including the hollow portions of said fitting. 115

6. In a car heating system, the combination with a train pipe of radiating means, a pair of hollow fittings surrounding a train pipe and spaced one from the other, a supply pipe leading to one of said fittings, a 120

pipe extending parallel with the train pipe and connecting one fitting to the other, fluid conduits connecting the fittings with the radiating means, and controlling devices for said radiating means which are attached to and lie adjacent to said fitting and communicate with the interior thereof.

7. In a car heating system, the combination with a train pipe of radiating means, a pair of hollow fittings surrounding the train pipe and spaced one from the other, a supply pipe leading to one of said fittings, a pipe extending parallel with the train pipe and connecting one fitting to the other, fluid conduits connecting the fittings with the radiating means, a vapor regulator and a steam trap attached to and lying adjacent to said fitting and communicating with the interior thereof.

8. In a car heating system, the combination with a train pipe of a water circulating coil, a steam heating device for the water circulated through the water coil, a pipe leading from the train pipe to the steam heating device, a steam circulating coil having a fourway valve, a fitting having a steam duct therein, a pipe leading to said fitting and adapted to receive steam when steam is admitted to said steam heating device, a fluid conduit connecting the fitting with the circulating coil, and a vapor regulator attached to and lying adjacent to said fitting and pipes connecting the fourway valve with the vapor regulator, said fourway valve being constructed so that when the steam circulating coil is closed, steam will circulate through said fitting, vapor regulator and the pipes leading therefrom and thereto.

9. In a car heating system, the combination with a train pipe of a water circulating coil, a steam heating device for the water circulated through the water coil, a pipe leading from the train pipe to the steam heating device, a steam circulating coil having a fourway valve, a fitting having a steam duct therein, a pipe leading to said fitting and adapted to receive steam when steam is admitted to said steam heating device, a vapor regulator attached to and lying adjacent to said fitting and communicating therewith, and pipes connecting the fourway valve with the vapor regulator, said fourway valve being constructed so that when the steam circulating coil is closed, steam will circulate through said fitting, vapor regulator and the pipes leading therefrom and thereto, and a steam trap attached to said fitting and communicating with the steam duct thereof.

10. In a car heating system, the combination with a train pipe of a water circulating coil, a steam heating device for the water circulated through the water coil, a pipe leading from the train pipe to the steam heating device, a steam circulating coil hav-

ing a fourway valve, a fitting having a steam duct therein, a pipe leading to said fitting and adapted to receive steam when steam is admitted to said steam heating device, and a vapor regulator attached to and lying adjacent to said fitting and communicating therewith and pipes connecting the fourway valve with the vapor regulator, said fourway valve being constructed so that when the steam circulating coil is closed, steam will circulate through said fitting, vapor regulator and the pipes leading therefrom and thereto, said fitting being constructed so as to surround the train pipe.

11. A fitting for a car heating system comprising a tubular member adapted to surround the train pipe of the car, formed with a hollow lateral projection for conducting live steam from the train pipe to other elements of said heating system and tapped for connection to a steam trap.

12. A fitting for a car heating system comprising a tubular member adapted to surround the train pipe of the car, formed with a hollow lateral diagonally arranged projection for conducting live steam from the train pipe to other elements of said heating system and tapped for connection to a steam trap.

13. A fitting for a car heating system comprising a tubular member adapted to surround the train pipe of a car, formed on opposite sides with hollow projections and with a hollow transverse member connecting said projections for conducting live steam from the train pipe to the other elements of said system and tapped for connection to a steam trap.

14. A fitting for a car heating system comprising a tubular member adapted to surround the train pipe of the car, formed with oppositely arranged lateral diagonal hollow projections and with a hollow connecting member underneath the tubular member, and tapped at the upper and lower ends of said diagonal projections to provide connections for conducting live steam from the train pipe to other elements of said system and for communication with a steam trap.

15. A fitting for a car heating system comprising two members attached to surround the train pipe of a car, means for securing said members together in operative position on the train pipe; one of said members being formed with a steam duct and being tapped to provide connections for the other elements of said heating system.

16. A fitting for a car heating system comprising a member channeled so as to fit the train pipe of a car, an upper member arranged in the channel of the first-named member above the train pipe, means for securing said members together; the lower member being formed with lateral dia-

ually extending ducts and with a transverse duct connecting the lower ends of said diagonal ducts, and being tapped so as to provide connections for the other elements of the 5 heating system.

17. A fitting for a car heating system comprising a member channeled so as to fit the train pipe of a car, an upper member arranged in the channel of the first-named 10 member above the train pipe, means for securing said members together; the lower member being formed with lateral diagonally-extending ducts and with a transverse duct connecting the lower ends of said diagonal ducts, and being tapped so as to provide 15 connections for the other elements of the heating system, and means for supporting said fitting from the car independently of said train pipe.
18. A fitting for a car heating system comprising two members attached together to embrace the train pipe of a car, means for securing said members together, one of 20 said members being formed with a steam duct and being tapped at different points 25

along said duct to provide connections for other elements of said heating system.

19. A fitting for a car heating system comprising upper and lower members attached together to surround the train pipe 30 of a car, and means for securing said members together, one of said members being formed with a duct and being tapped at different points along said duct to provide connections for other elements of said heating 35 system.

20. In a car heating system, the combination with a train pipe of radiating means, a fitting loosely surrounding the train pipe and having hollow passageways about said 40 pipe, a fluid conduit which includes the hollow passageways of the fitting and communicates with the train pipe at a point removed from the fitting and with the radiating means, and a steam trap attached to 45 and lying adjacent to said fitting.
